FUEL FEED

Emil Richard Klemm, Jr., Lincolnwood, Ill.

Application November 5, 1954, Serial No. 467,052

6 Claims. (Cl. 123—136)

My invention relates to motor cars and includes among its objects and advantages substantial immunity to vapor lock at relatively insignificant cost.

In the accompanying drawings:

Figure 1 is a diagrammatic side view of the engine of a conventional motor car, indicating the application of equipment according to the invention thereto;

Figure 2 is a similar side elevation, indicating special expedients for additional cooling;

Figure 3 is a side elevation of a combined fuel filter and vapor trap; and

Figure 4 is a transverse section through the unit of Figure 3.

Referring first to Figures 3 and 4, the base casting 10 has an inlet 12 and an outlet 14 arranged coaxially and threaded to receive conventional pipe connections 16. The body includes the peripheral outer lip 18 which extends down to an annular shelf 20. The inner edge of the shelf extends down to the central floor 22. From the center of the floor 22 the trap tube 24 extends up. The conventional cup-shaped filter element 26 is pressed down against the cork gasket 28 by the compression spring 30 which is affixed to the body of the filter by having two turns 32 at its lower edge, of a size to be forced over the filter by slight expansion, so that they grip the filter. The transparent housing 34 rides on the sealing gasket 36 which rests on the shelf 20.

Means are provided for holding the parts in assembled position and for taking them apart quickly and easily for inspection, or for replacement of the filter element. The bail 38 has inturned ears to pivot it on a transverse axis at 40, and at the top its bight 42 is pressed or welded into a groove in the head 44 of a stud 46. The stud 46 carries the threaded wing nut 48, and the inverted cup washer 50 is seated in a shallow central depression 52 in the top of the housing 34.

In the position of Figure 4, the nut 48 has been turned to jam the housing 34 firmly against the gasket 36. To disassemble the parts, the user merely screws the nut 48 up as high as it will go, while holding the housing 34 in the position of Figure 4 with the other hand. This leaves enough clearance for the cup 59 to rise out of the socket 52 and the entire bail and stud and nut can be swung over in either direction from the position of Figure 3. Then the housing 34 and the cup 26 can be simply picked up and replacements set in place.

Referring now to Figure 1, I have indicated a conventional internal combustion engine of the V-8 type at 54, provided with the fan 56 and the fuel pump 58 and the carburetor 60 surmounted by an air filter 62 and delivering explosive mixture to the inlet manifold 64. All these parts are conventional. To equip such a power plant with the device of Figures 3 and 4, it is only necessary to cut the fuel line leading from the pump 58 up to the carburetor 60, and insert the device. As thus assembled in Figure 1, there is a riser pipe 64 and the short carburetor connection at 66, which are parts of the pipe that was there before the installation was made.

2

The body 10 has been inserted between the pipes 64 and 66 with the housing 34 extending vertically upward. Fuel coming up from the pump 58 rises through the gate 68 (Fig. 4) into the annular space outside the filter 5 and percolates through inside the filter and then down the trap tube 24 and out through the outlet 14 to the carburetor. With or without the trap tube 24, it will be obvious that in case of the abnormal temperature rise which causes vapor lock, any volatile ingredients of the fuel, that have been vaporized, will rise to the top of the housing 34, and a substantial volume of gas can be stored there without interrupting the regular flow of the fuel to the carburetor. Furthermore, because this housing dome receives the blast of air from the fan 56, the cooling action of the blast of air tends to condense the volatile ingredients, and such condensation causes liquid to refill the entire dome, while the gases which might have caused trouble return to liquid condition and join the rest of the fuel on its way to perform its proper function.

With the trap tube 24 and with the device mounted with the dome uppermost as illustrated in the drawings, if there should be traces of water in the motor fuel, that water will accumulate in the lower part of the dome up to the top of the trap tube 24, and will not go to the carburetor and interfere with engine operation. The amount of storage provided is ample to take care of traces of water in all but the lowest quality of motor fuels. If water accumulates and operation becomes irregular, there is nothing easier than to lift the dome and filter off and rinse them out and put them back on.

With the trap tube 24 it will also be obvious that the same device will intercept and store both liquid and vapor with the dome extending down instead of up. But in that case the vapor will accumulate around the tube 24, where the body 10 more or less prevents the user from observing its presence, while the water will accumulate in the bottom of the now inverted dome 34. Accordingly, the preferred position for installation is that illustrated. Practical operation over an extended period has demonstrated that about ninety-nine percent (99%) of the difficulties due to vapor lock during hot weather are eliminated by the mere presence of the device. However, when extreme conditions result in vapor lock in a power plant according to Figure 1, the user need only lift the hood and glance at the dome to ascertain whether his difficulties are due to vapor lock or not, and if a gas space is observed in the top of the dome, a glass of water poured over the dome will eliminate the trouble.

Others may readily adapt the invention for use under various conditions of service by employing one or more of the novel features disclosed or equivalents thereof. In Figure 2 I have illustrated the same power plant 54 equipped for service in such a climate as that of Death Valley, California, or the Sahara Desert. If the motor vehicle is provided with an air conditioning unit 68, a branch pipe 70 can deliver coolant to a cooling coil 72 surrounding the dome 34. With or without this cooling expedient, the dash board 74 can be equipped with a water bottle 76 with its discharge controlled from the dash by a needle valve 78, so that a slow water drip can be delivered to the outer surface of the dome 34. Because the dome is in the air blast from the fan 56, the rapid evaporation of the water from the wet outer surface of the dome will provide a strong cooling action.

As at present advised with respect to the apparent scope of my invention, I desire to claim the following subject matter.

I claim:

1. Fuel feed means for an internal combustion engine having a carburetor located at an elevation not materially less than the top of said engine, comprising, in combination: a fuel intake conduit located at a level

near the bottom of said engine; a fuel pump at substantially the same level as said intake conduit; a riser for conveying fuel from said pump up to said carburetor; and a chamber for segregating vapor associated with said riser and located at the highest point in said riser.

2. Fuel feed means according to claim 1, in which said segregating chamber is at a higher level than said carburetor.

3. Fuel feed means for an internal combustion engine comprising, in combination: a fuel intake conduit; a pump receiving liquid from said intake conduit; a carburetor; a delivery conduit receiving liquid from said pump and delivering it to said carburetor; said intake conduit and pump being both at a low level near the bottom of the engine; said carburetor being at a high level near the top of the engine; said delivery conduit rising from the pump level to the carburetor level; and trap means interpolated in said delivery conduit at a level higher than the fuel level in said carburetor; said trap means including an inverted dome for receiving and accumulating vapor emanating from the fuel.

4. Fuel feed means according to claim 3 in which the said dome is transparent and accessible, whereby the presence of vapor may be readily observed, and a cooling medium, such as cold water, may be readily applied to said dome.

5. Fuel feed means according to claim 3 in which said dome also houses a filter element; said dome and

5 filter element defining an annular clearance space outside said element and inside said dome; said dome and element having a unitary support defining an inlet opening upwardly outside said element into said annular clearance space, and an outlet debouching inside said element; whereby the fuel flow rises through sediment accumulating in said annular clearance space.

6. Fuel feed means according to claim 5 in which said outlet has an upwardly opening tubular receiving end; said receiving end extending up materially below the lower end of said element and defining a second, inner, annular clearance space between itself and said element; said second clearance space being sealed at its lower end by said support; whereby said second clearance space is a dead end for storage of impurities in the fuel, of greater density than the fuel, such as water.
